EXTRACTOR LOAD BREAKER

Joseph E. Veturino, New Bedford, Mass.

Application June 17, 1949, Serial No. 99,800

9 Claims. (Cl. 210—74)

1

This invention relates to load breakers for extractors. It is particularly concerned with load breakers for commercial extractors of the type now in common use in commercial laundries. A typical form of such extractor comprises two identical semi-cylindrical halves, each having a hinged drop bottom normally latched in closed position during the extracting operation. This bottom is unlatched after the water has been extracted to permit the load to be dropped out through the bottom opening.

One of the problems present in extractors of all types, whether of the drop bottom form in which the load is removed from the bottom or of the earlier conventional form in which the load is removed from the top, is the freeing of the load from the extractor wall. This wall is a circular sheet of metal having a very large number of perforations therethrough by which the water escapes as the extractor is whirled at high speed. The centrifugal force developed is so great that the load, generally cloth in various forms such as clothing, sheets, pillow cases, diapers, etc., is forced into the wall perforations to such an extent that it becomes firmly anchored to resist subsequent removal.

It has therefore been necessary heretofore to spend considerable time and effort in pulling the clothes away from the extractor wall by hand. The slow detaching movement by hand is preferably toward the center of the extractor as that is the direction in which the load can be most easily separated from its engagement with the wall perforations. When the load consists of relatively fragile articles such as handkerchiefs, diapers and other soft open-weave cloths, the operator in pulling the load loose may unwittingly tear the articles unless great care is used. Damaged articles, of course, must be paid for and there is commonly a high damage loss incident to the current method of freeing the load.

The present invention is designed to overcome the disadvantages aforesaid by providing a new and novel means for quickly and safely freeing the load from the extractor wall to such an extent that with the hinged bottom open, the load will be capable of falling of its own weight through the bottom opening. Under existing conditions this does not occur as the weight of the load is not sufficient in itself to enable it to pull away from its engagement in the wall openings.

The extractor load breaker by which name the present invention will be known is particularly suitable for use with the divided type of ex-

2

tractor basket. A single load breaking unit only is needed in each semi-circular basket. Each load breaker unit will be placed at the mid-point of the wall of each half basket so that the units in the two half baskets will be diametrically opposite each other. In this way the dynamic balance will be unchanged during the extracting operation and the dislodging force of the load breaker when actuated will be applied centrally of the load in each half basket. By having the force applied centrally the clothes will be pulled away from the basket wall to an equal extent on both sides of the load breaker, thus accomplishing uniform and quick freeing of the load from the wall.

The present invention also contemplates the utilization of the falling weight of the basket bottom after it is unlatched. The bottom is connected in a new and novel manner to the load breaker elements so that it will give a quick powerful pull that will readily commence the initial separation of the load from the wall. After the bottom has swung downwardly to a position far enough to have freed the load, the connection between the bottom and the load breaker will automatically separate and the parts will then fall to vertical position out of the path of the dislodged load which is then able to fall freely from the basket to a collection point below.

Other objects of the invention will appear as the description proceeds with the aid of the accompanying drawings in which

Fig. 1 is a plan view of a pair of conventional extractor baskets showing the load in the approximate position it will assume after the liquid has been extracted by whirling. The load is broken away in part to show more plainly the load breaking mechanism.

Fig. 2 is an enlarged vertical section on the line 2—2 of Fig. 1.

Fig. 3 is a vertical section similar to Fig. 2 with the load breaker mechanism being operated by the falling bottom.

Fig. 4 is a plan view on the line 4—4 of Fig. 3.

Fig. 5 is a view similar to Figs 2 and 3 with the load breaker mechanism disconnected from the bottom and showing the load falling through.

Fig. 6 is a fragmentary view looking to the left on line 6—6 of Fig. 2.

Fig. 7 is a fragmentary view looking upward on the line 7—7 of Fig. 2.

Fig. 8 is a sectional plan view on the line 8—8 of Fig. 2.

Fig. 9 is a perspective enlarged detailed view of

the connecting hook mounted on the hinged bottom.

Fig. 10 is a fragmentary plan view similar to Fig. 8 with the load omitted.

Referring to Fig. 1, a conventional extractor basket is shown, consisting of two halves 2 and 3. Each half is identical with the other and a description of one half will therefore suffice as a description of the other. Reference hereafter will be made to the left half basket 3. This comprises a semi-cylindrical perforated wall 4 full of multiple perforations 6 (see Figs. 2 and 6) and having an inwardly turned upper lip or flange 8. The bottom is closed by a semi-circular member 10, suitably hinged at each end at 12 and 14. The bottom is held in normal closed position by means of a latch 16 which may be sprung outwardly through a vertical opening in the wall to release the bottom so that it may swing downwardly.

The half basket has a straight unperforate inner side 18 which at the center has a conical section 20 which overlies the curved up-turned inner edge 22 of bottom 10. Thus, when the bottom is in horizontal latched position, the half basket may be filled with clothes from which the water is to be extracted.

It is customary in present day construction to provide rollers or casters as an integral part of the bottom so that each half basket when out of the whirler may be conveniently moved. The casters or rollers are shown in Fig. 1 at 24, 26 and 28, the axles of which are supported by forks of the type indicated in Fig. 2 at 30. The caster supports are securely mounted in turn to the underside of upwardly extending recesses in the bottom 10. The three recesses in the bottom of basket 2 are indicated at 32, 34 and 36. These recesses are formed by suitably shaped metal cups which are riveted to the bottom around cut-away areas through which the casters extend downwardly. The present invention, however, will operate just as effectively with a basket of the type in which the bottom does not have casters.

The latch 16 that holds the bottom 10 in normal position may be swung outwardly through a vertical opening in the lower side of the basket through the use of a suitable tool whereupon the bottom may drop of its own weight. To relatch the bottom, it is merely necessary to swing it up until the latch has snapped into locking position. A stop 38 limits upward movement of the bottom.

The description thus far has been of a typical basket of the type now found in common use in commercial laundries. The load breaker mechanism which will be described hereinafter is applied to this basket either as an accessory after the basket is already in use or it may be built into the basket as an integral part at the time of manufacture.

It will be understood that after the two half baskets have been loaded with wet clothes, they will be lowered into a closely fitting outer basket which is arranged for high speed rotation. As the extracting operation proceeds, the water will pass outwardly through the perforations of the baskets and the clothes will be compacted until they have reached approximately the position shown by the line 40 in Figs. 1 and 2. At this position there is an appreciable space between the inner circumference of the clothes and the tapered center portion 20. When the extracting operation is finished and the bottom 10 is unlatched, it will be found in the ordinary situation that the clothes will not drop through the bottom opening because they have become firmly at-

tached to the basket wall by means of the small portions of the clothes which centrifugal force has driven into the multiple perforations in the basket wall.

Applicant has, therefore, found it expedient to provide mechanical means as a substitute for the hand operation which up to the present has been used to free the clothes from the basket wall. This load breaker mechanism comprises a unit which is positioned vertically along the inside of the basket wall, midway of its circumference. It lies flat against the wall so as not to interfere with the clothes during the extracting operation and is connected to the bottom in such manner that when the bottom is unlatched it will, in dropping, actuate the load breaker mechanism to a degree sufficient to free the load from the wall over a substantial arc so that the weight of the load thereafter will be sufficient to pull the clothes free from that part of the wall from which they have not been heretofore disengaged by operation of the load breaking mechanism.

Immediately upon freeing the load, the mechanism is automatically released from the bottom so that all parts may drop to a vertical position eliminating any obstruction to the free fall of the clothes from the basket.

The mechanism that has just been briefly described comprises a link in the form of a flat strip 42 hinged at 44 to the top flange 8. Strip 42 extends to a point close to the wall 4. It is pivotally connected at its end 46 to a shallow, wide vertical channel 48. This channel in turn extends downwardly to a point a short distance above stop 38 where it in turn is hingedly connected at 50 to a long link 52 having a sloping portion 53 and downwardly turned sides 54 which overlie the sides of the caster recess or box 32. Sloping portion 53 in turn is connected to a flat strip 56 which lies close to the bottom 10. Portion 53 and strip 56 constitute the link 52. The end of strip 56 has welded thereto a U-shaped loop of bar stock 58 which is arranged for engagement with a novel type of automatically releasing hook 60. See Fig. 9. Hook 60 is securely affixed to bottom 10 by screws or bolts 62 and 64.

When the bottom of the basket is closed, the load breaker mechanism will be close against the wall and bottom of the basket as illustrated in Figs. 1, 2, 6, 7, 8 and 10. When the extracting has been completed and the basket has been moved to a position where the clothes are to be dropped, latch 16 is operated to release the bottom which immediately commences to swing downwardly carrying with it link 52 and all the other related parts. The clothes have, of course, been pressing with great force against channel 48 but the pull on link 52 by the heavy downwardly swinging bottom 10 is sufficient to move channel 48 downwardly and to the right as illustrated in Fig. 3. This pulls the load away from the wall 4 as shown in Fig. 4 at 66 and 68. Since channel 48 is symmetrically disposed with respect to the load, the activating force will be in a radial direction inwardly which provides maximum effectiveness in loosening the load from the wall. The inner circumference of the load will be moved to the position suggested by the lines 70 and 72 in Fig. 4 and at 74 in Fig. 3. At this point it may have reached slight engagement with the bottom of cone 20.

While the weight of the bottom itself pulling on link 52 may be sufficient to cause adequate dislodgement of the load, it is customary, however, for the operator to push with his hand

against the bottom so as to increase the dislodging force. As this is done, the bottom is moved more toward the vertical to reach the point at which the loop 58 will automatically disengage itself from hook 60.

It can be seen in Fig. 9 that hook 60 has an upturned lip 76 reinforced by longitudinal struts 78 and 80. Lip 76 is adapted to engage loop 58. As lip 76 assumes a more vertical position as the bottom swings open, a point will be reached where loop 58 will slide upwardly off lip 76 whereupon the link 52 and bottom 10 will be freed of each other. When this occurs the bottom and link 52 will both drop to vertical position as shown in Fig. 5. Thus the space at the bottom of the basket is completely open so that the load now dislodged may fall downwardly and out under its own weight.

In order to free the channel 48 as completely as possible from the load when the bottom 10 and link 52 have separated, a coil spring 82 similar in general to the type used on door hinges is incorporated at hinge 44. This spring is designed to swing link 42 upwardly to the position shown in Figs. 2 and 5, as soon as the downward pull on channel 48 has been released. In this way the channel 48 is not only separated from the load but is restored to initial position prior to the reclosing of the bottom.

In Fig. 9 it will be noted that hook 60 has a downturned lip 84 which extends away from the bottom a greater distance than lip 76. This lip 84 serves two purposes when the bottom has reached vertical position, as shown in Fig. 5. Lip 84 will prevent the downwardly moving clothes from catching on lip 76. Thereafter, when the bottom is to be closed to be reset to the position shown in Fig. 2, the operator swings link 52 toward the bottom and at the same time swings bottom 10 upwardly toward latched position. Where the arc of loop 58 intersects the arc of lip 76, the two may be re-engaged and then as the operator continues to swing the bottom 10 upwardly, lip 84 will press against loop 58 to prevent the parts from becoming unhooked as the bottom continues upwardly toward horizontal relatched position.

From the foregoing description it will be seen that channel 48 is swung through a downward inward arc as the load breaking operation proceeds. It also remains during this period of movement substantially parallel to the wall. This result is achieved automatically as the result of the pressure of the load over the length of member 48. The load breaking effort would be insufficient if the channel 48 did not move away from the wall over its entire length but instead, for example, merely pivoted at 46 without being pulled downwardly as well as inwardly as shown in Fig. 3. It will also be seen that downward inward movement of channel 48 results in corresponding downward and inward swinging movement of link 42 which assists in freeing the load at the top as it presses downwardly and inwardly on that part of the load with which it is in contact.

While the pull on channel 48 has been provided by link 52 connected with bottom 10, nevertheless it will be understood that other mechanical means might be devised for causing a corresponding load breaking movement of link 42 and channel 48. Such mechanism would be arranged to move these parts downwardly and inwardly by lever means other than the bottom 10. In any case, however, it will be noted that the load breaking force is applied symmetrically of the

load and in a radial direction inwardly, so that the load is pulled away from the wall uniformly on both sides of the channel and substantially uniformly along the vertical dimension of the load.

The invention has been disclosed herein in a brief form but it is not intended that it shall be limited thereby but only by the appended claims.

I claim:

1. An extractor load breaker for freeing a load from the perforated wall of a centrifugal extractor basket of the drop bottom type and having an inwardly extending top flange, said load breaker comprising in combination with said basket a vertically extending member normally positioned close to and at the midpoint of said basket wall so that the load will be disposed symmetrically thereto, a first link connecting said member to said flange, a second link connecting said member to said bottom when the latter is in closed position, said member and links operable upon downward movement of said bottom to move said member downwardly and inwardly a distance sufficient to free said load from said wall over a substantial arc on both sides of said member and means compelling disconnection of said second link and said bottom when said bottom has swung downwardly from its normal closed horizontal position through a determinable angle.

2. An extractor load breaker for freeing a load from the perforated wall of a centrifugal extractor basket of the drop bottom type and having an inwardly extending top flange as set forth in claim 1, said first link having spring means associated therewith for constantly urging said link upwardly toward the under side of said flange.

3. An extractor load breaker for freeing a load from the perforated wall of a centrifugal extractor basket of the drop bottom type and having an inwardly extending top flange as set forth in claim 1, said means for connecting said second link and bottom comprising a hook affixed to said bottom, means on said second link for engaging said hook, said hook and second link adapted for automatic disengagement when said bottom has swung downwardly at least far enough to cause said load to be substantially freed from said wall.

4. An extractor load breaker for freeing a load from the perforated wall of a centrifugal extractor basket of the drop bottom type and having an inwardly extending top flange as set forth in claim 1, said first link hinged to said flange near the inner periphery thereof and of such length as to be capable of swinging movement upwardly to lie close against the underside of said flange with said member close to said basket wall, said second link being substantially longer than said first link.

5. An extractor load breaker for freeing a load from the perforated wall of a centrifugal extractor basket of the drop bottom type and having an inwardly extending top flange as set forth in claim 1, said bottom having an upwardly extending recess in vertical alignment with said member with a caster located in said recess, said second link shaped to overlie and conform generally with the top of said recess and the bottom adjacent thereto.

6. An extractor load breaker for freeing a load from the perforated wall of a centrifugal extractor basket of the drop bottom type and having an inwardly extending top flange, said

load breaker comprising in combination with said basket a plurality of links in series, the free end of one of the end links being pivotally connected to said flange inwardly of said wall, the other end link having on its free end a hook engaging member, another link between said end links normally being in vertical position against said wall, a hook attached to said bottom adapted to engage said hook engaging member, and a lip arranged to overlie said hook when said bottom is in vertical position to prevent clothes being discharged from said basket through the bottom opening from being caught on said hook.

7. An extractor load breaker for freeing a load from the perforated wall of a centrifugal extractor basket of the drop bottom type and having an inwardly extending top flange, said load breaker comprising in combination with said basket a member normally located in vertical position close to and at the mid-point of said basket wall so that the load will be disposed symmetrically thereto, a first link connecting said member to said flange, a second link connecting said member to said bottom when the latter is in closed position, the connection between said second link and bottom comprising a hook affixed to said bottom and means on said second link for engaging said hook, said hook and second link adapted for automatic disengagement when said bottom has swung downwardly at least far enough to cause said load to be substantially freed from said wall, said second link being longer than the straight line distance from the point of connection of said second link with said member to the hook on said bottom when said member is in normal position close to said wall and said bottom is in closed position.

8. An extractor load breaker for freeing a load from the perforated wall of a centrifugal extractor basket of the drop bottom type and having an inwardly extending top flange, said load breaker comprising in combination with said basket a member normally located in a vertical position close to and at the mid-point of said basket wall so that the load will be disposed symmetrically thereto, a first link connecting said member to said flange, a second link connecting said member to said bottom when the latter is in closed position; the connection between said

second link and bottom comprising a hook affixed to said bottom and means on said second link for engaging said hook, said hook and second link adapted for automatic disengagement when said bottom has swung downwardly at least far enough to cause said load to be substantially freed from said wall, said second link being sufficiently longer than the straight line distance from the point of connection of said second link with said member to the hook on said bottom when said member is in normal position close to said wall and said bottom is in closed position to enable said second link to conform generally to the configuration of the bottom between the lower end of said member and hook.

9. An extractor load breaker for freeing a load from the perforated wall of a centrifugal extractor basket of the drop bottom type and having an inwardly extending top flange, said load breaker comprising in combination with said basket, three links in series, a first link pivoted to said flange and extending radially outwardly from said pivot, a second link longer than said first link extending vertically close to said basket wall for a major portion of the vertical dimension of said wall, a third link extending from the lower end of said second link along said bottom to a point of connection with said bottom which point of connection is closer to the axis of said basket than the pivot of said first link on said flange, and connecting means between said third link and said bottom, said means acting to draw said third link inwardly and downwardly as said bottom swings downwardly on being released for opening, said connecting means including automatic releasing mechanism for freeing said third link from said bottom when the angle between said bottom and third link has increased to a predetermined degree.
